CLAIM

The ornamental design for an expandable wing aircraft as shown and described.

DESCRIPTION

FIG. 1 is a front top perspective view of an expandable wing aircraft, showing our new design;

FIG. 2 is a rear bottom perspective view of the expandable wing aircraft of FIG. 1;

FIG. 3 is a front elevational view of the expandable wing aircraft of FIG. 1;

FIG. 4 is a rear elevational view of the expandable wing aircraft of FIG. 1;

FIG. 5 is a first side elevational view of the expandable wing aircraft of FIG. 1;

FIG. 6 is a second side elevational view of the expandable wing aircraft of FIG. 1;

FIG. 7 is a top plan view of the expandable wing aircraft of FIG. 1; and,

FIG. 8 is a bottom plan view of the expandable wing aircraft of FIG. 1.

The expandable wing aircraft is shown with a symbolic break in its length. The appearance of any portion of the article between the break lines forms no part of the claimed design. Additionally, the dash-dash broken lines in the drawings are included for the purpose of illustrating portions of the expandable wing aircraft that form no part of the claimed design. The dot-dash-dot broken lines in the drawings are included for the purpose of defining the boundary of the claim, it being understood that the region between the dot-dash-dot broken lines and the dot-dash-dot broken lines themselves form no part of the claimed design.

1 Claim, 6 Drawing Sheets
